TENSION DEVICE

Willard T. Munson, Dunmore, Pa., assignor to Henry E. Collins and Albert B. Collins, both of Scranton, Pa., copartners, doing business as Collins Supply & Equipment Co.

Application July 15, 1933, Serial No. 680,614

5 Claims. (Cl. 242—150)

The present invention relates to a combined tension device and thread cleaner, and has for an object to provide a device of this character embodying these features, and supporting or carrying means therefor adapting the device to various mountings or installations on different types of winding, coning and other thread utilizing machines.

Another object of the present invention is to provide a device of this character wherein the bracket, head or support is constructed in interchangeable sections upon which are mounted the various portions of the combined device so as to maintain a desired and uniform tension upon the thread during the cleaning action and under all conditions of installation or mounting of the device, and wherein the cleaning and tension action may be regulated according to the different types of machines and the nature of the thread which is wound.

The invention also aims to provide an improved type of thread tension device and cleaner having a thread guide embodying a shiftable or adjustable notch member having a plurality of notches therein adapted to be brought one at a time into line with the thread guide as the surfaces or walls of the notches become worn so that by slight adjustment the device may present a renewed thread notch to the guide.

A further object of the present invention is to provide an improved construction for removing initial accumulations of slugs and other adhering particles and portions adhering to the thread and which would otherwise pass through the device and be wound upon the bobbin, cone or the like.

With the foregoing and other objects in view, the invention will be more fully described herein-after, and will be more particularly pointed out in the claims appended hereto.

In the drawings, wherein like symbols refer to like or corresponding parts throughout the several views,

Figure 1 is a side elevation, partly in section of a portion of a spool winder showing one installation of the combined tension device and thread cleaner of the present invention.

Figure 2 is a detail perspective view of the thread cleaner adjusted for mounting upon the transverse bar of the spooling machine.

Figure 3 is a top plan view of the tension portion or head of the device with the rotary weight removed and showing the path of a thread in the device.

Figure 4 is a longitudinal vertical section taken through the same on the line 4—4 of Figure 3.

Figure 5 is a side elevation of the tension head obverse to the showing in Figure 4.

Figure 6 is an outer end view thereof showing the recess or leading-in guide for the thread.

Figure 7 is an opposite end elevation thereof showing the tension equalizing bar.

Figure 8 is a fragmentary section view of different type of a spool winding machine, having the combined tension device and thread cleaner adjusted thereto.

Figure 9 is a top plan view of the device with the rotary weight removed and adjusted as shown in Figure 8.

Figure 10 is a longitudinal section taken through the same on the line 10—10 of Figure 9, and

Figure 11 is an inner end elevation of the device.

Referring now to the drawings, and first to the arrangement shown in Figures 1 to 7, 10 designates the frame of a spool winding machine carrying a winding spool 11 and which is provided below the spool with the usual cross bar 12 carrying a bracket arm 13 which may have a socket 14 at its lower end for embracing the rod 12 and adjustably secured to the rod 12 by a set screw 15 or the like. The bracket 13 also carries an arm 16 upon which is mounted a bobbin 17 or the like from which the thread 18 is taken to be wound upon the spool 11.

The bracket arm 13 is provided at its upper end with a laterally extending stud 19 which is employed for supporting certain portions of the improved tension device and thread cleaner. The device comprises a head or plate 20 having a flat upper surface and provided intermediately with a depending web 21 with socket openings 22 therein and which also has a cap plate 23 adjustably connected by a set screw 24 to the web 21 and which overlies the socket openings 22 for closing the latter and binding the head or plate 20 on a bar, the stud 19, or any other suitable support.

The head or plate 20 is provided in its outer end with a flaring recess 25 the walls of which are adapted to engage the thread 18 and direct it into a throat or narrow slot 26 which is disposed lengthwise of the head 20 and substantially intermediate the edges thereof.

Rising from the central portion of the head 20 is a pivot pin 27 and the upper surface of the head is provided with a concentric depression 28 about the base of the pin 27, and from Figure 3, it will be noted that the pin 27 is offset laterally with respect to the throat 26 so that the thread 18 may be drawn from the throat across the remote side of the pin 27 and inwardly across the head 20. The thread 18 thus bridges the depression 28 and the latter serves to catch any particles removed from the thread by rubbing action.

The head 20 is also provided, at the inner side of the pin 28, with a slot or opening 29 of substantially triangular or other suitable configuration which opens into the depression 28 and which is disposed beneath the thread 18 as it passes from the depression 28. The opening 29 pro-

vides a relatively sharp shoulder 30 over which the thread 18 rubs so as to catch and hold any accumulations adhering to the thread and passing therewith from the depression 28 so that the accumulations may drop downwardly through the opening 29 and fall out of the device. The pin 27 is removably seated at its lower end in the head 20 so that the pin 27 may be lifted, at least to a small extent, upwardly from the head, and the depression 28 is provided in an adjustable disc 31 which is fixed to the pin 27 and which is countersunk in the upper face of the head 20.

The marginal edge portion of the disc 31, as shown in Figure 4, projects into the upper portion of the throat or groove 26 and the disc 31 is provided at suitably spaced apart points with transverse grooves 32 which correspond to the inner end of the throat 26 so as to provide upper rubbing edges for the groove 26 over which the thread 18 may pass. The disc 31 may be slightly raised out of the head 20 and turned to interchange the grooves 32 relative to the throat 26 so that the rubbing edges, provided by the grooves 32, may be renewed from time to time. The head 20 is provided at one side of the disc 31 with a key or retaining pin 33 fixed upon the head and adapted to receive an adjacent notch 32 for holding the disc 31 from turning out of its adjusted position.

Of course the pin 33 is located on the head relatively to the throat 26 and to the number and spacing apart of the peripheral grooves or recesses 32 in the disc 31. It will also be noted that the disc 31 is provided with triangular slots 34, one for each notch 32 and disposed in substantial radial register therewith at the opposite side of the pin 27 so that each notch 32, when adjusted into register with the throat 26 will have a corresponding opening 34 in register with the opening 29 of the head. Thus, the rubbing edges and surfaces are all disposed upon the disc 31 and may be interchanged from time to time as they wear.

The inner end of the head 20 is provided with a depending end wall 35 which carries a connecting screw 36 having its head engaging the inner side of a comb 37 and which has its threaded portion projecting outwardly through the wall for receiving a retaining nut 38. The comb 37 is vertically slotted to receive the bolt or screw 36 and is provided with a set of comb teeth 39 which are inclined upwardly and outwardly toward the throat 26 of the head. The comb 37 is adapted to be adjusted into position immediately beneath the thread 18 as it passes inwardly from the upper surface of the head 20. The retaining nut 38 is preferably of a type which may be adjusted only by use of a special tool, and for this purpose the outer end of the nut 38 is preferably tapered and provided with an axial non-circular bore 40 for receiving a rectangular or other suitably shaped shank for interlocking engagement with the nut 38 to turn it. Thus, when the comb 37 is adjusted such adjustment cannot be disturbed except by a duly authorized person having the specially constructed tool.

The head 20 is provided at its inner end, and at one side of the wall 35, with a seat or shoulder 41 which extends vertically and which serves to support and hold in proper relation to the head the interchangeable sections thereof, as shown in Figures 3 and 9.

In the adjustment shown in Figure 1, the head 20 is provided with a tension equalizing bar

42 which, as shown in Figure 7 particularly, extends entirely across the head 20 and is provided with an attaching shank 43 at one end conforming to the shoulder or seat 41 and held in interlocking engagement thereagainst by a screw 44 or the like. The shoulder 41, as shown in Figure 3, is stepped sufficiently to hold the shank 43 from turning and to thus support the tension equalizing arm 42 horizontally across the inner end of the head.

As shown in Figures 1 and 4, the thread 18 passes across the upper face of the head 20 and inwardly beneath the bar 42 and thence upwardly over the transverse bar 45 of the winding machine so that the thread is maintained substantially in the plane of the head 20 at all positions of the bar 45 during the rise and fall thereof in winding the spool 11.

The transverse bar 45 is utilized, in the arrangement shown in Figure 1, for carrying the thread cleaning blades. In this instance the blades 46 are mounted in a bracket frame 47 and the frame 47 has a lower inner part providing a shank corresponding to the shank 43 of Figure 7, so that the bracket 47 may be interchanged with the shank 43 when it is desired to substitute the blade cleaner for the tension equalizing bar 42.

When it is desired, however, to dispose the cleaning blades 46 adjacent to the spool 11 or other device upon which the thread 18 is wound, a clamp bracket 48 is employed preferably made in two sections, the body portion of which is provided with the shoulder 41' adapted to receive the lower shank portion of the holder 47 for the blades 46. In this instance the thread 18 is carried upwardly from the bar 42 over the transverse bar 45 and thence inwardly through the blades 46 of the cleaner to the spool 11. Any loosening of fibers or foreign matter carried by the thread 18 incident to the rise and fall of the transverse bar 45 is thus caught in the final cleaning action as the thread passes through the blades 46, the blades being disposed at the inner side of the bar 45, as shown in Figure 1.

As shown in Figures 3 and 4 particularly, the pin or spindle 27 has freely rotatable thereon a gravity tension drum or disc 49 hollow in its upper side and carrying a desired number of weights 50 for urging the drum 49 downwardly against the thread 18 as the latter passes from the throat 26 and across the side of the pin 27. The purpose of said gravity tension drum is for enclosing the tension weights 50, thus preventing the accidental insertion of the thread between the tension weights instead of under tension drum or disc 49. Said tension drum by its enclosing the weights also prevents accumulation of waste and foreign matter between the weights which would eliminate frequent cleaning of said foreign matter which would otherwise accumulate between the weights. Another feature of tension drum or disc 49 is to facilitate automatic entering of the thread in its proper place under the tension drum which would be brought about by the rotation of the drum as a result of the friction of the thread against its side or top edge in case the thread were not guided by the hand of the operator in its proper place under the tension drum. The disc 49 is suitably weighted to impart the desired tension to the thread, and the thread is initially cleaned by the drawing and rolling action to which the thread is subjected as it passes about one side of the pin 27 and beneath the disc 49. The foreign matter

carried by the thread 18 is rubbed by the turning of the disc 49 and the drawing of the thread from the latter and is first caught in the depression 28 and thence carried by the thread 5 into the rear opening 34 and is detached from the thread by the abrupt shoulder 30 as the thread leaves the disc 31 for passage across the comb 39. The comb 39 catches any large slugs or particles which still hang to the thread, and 10 the thread is carried inwardly beneath the tension bar 42 and thence upwardly over the transverse bar 45, through the blades 46 and finally to the spool 11.

In the adjustment shown in Figures 8 to 11, 15 the clamp bracket 48 is dispensed with and the frame or bracket 47 of the blade cleaner is merely substituted against the shoulder 41 for the tension equalizing bar 42. The bar 42 is dispensed with in this adjustment so that the blades 46 serve not only as the final cleaner for the thread 18, but also as the equalizing device for holding the thread 18 in the plane of the head 20 during 20 the operation of the machine.

The head 20 with the gravity disc 49 provides 25 a tension device for the thread, the openings 34 and 29 respectively in the shiftable disc 31 and head 20 provide an outlet for the depression 28 to free slugs and other accumulations free from the thread 18 during the rubbing action 30 of the tension device. The shoulder or edge 30 of the disc slot 34 for the most part removes the accumulations from the thread 18 and the accumulations fall out through the opening 29 and the registering disc opening 34.

35 The comb 39 serves as a detector for any slugs or the like still carried by the thread 18 after it passes through the tension device. The final cleaning means, in the form of the blades 46 follows the comb and may be spaced from the head 20 on another part of the machine as shown 40 in Figure 1, or may be mounted directly on the inner end of the head 20 as a part thereof as shown in Figure 8.

The sequence of these devices thus described 45 and shown insures not only the proper tension on the thread 18 but also properly removes objectional slugs and other encumbrances on and 50 cleans the thread with the desired adjustment of both the cleaner and the tension device. This 55 is an essential combination and sequence as the tension device partially removes and loosens the slugs and the comb and cleaner are brought immediately into action to benefit by the loosening action of the tension device. The tension equalizing bar 42 and the clamp bracket 48 are removable so that for certain conditions the blade carrier frame 47 may be interchanged with the tension equalizing bar 42.

It is obvious that various changes and modifications may be made in the details of construction and design of the above specifically described embodiment of this invention without departing from the spirit thereof, such changes and modifications being restricted only by the 65 scope of the following claims.

What is claimed is:—

1. In a device of the character described, a head having a thread receiving guide slot in one end and having a pin socket offset laterally from the slot and a counter-sink about the socket and a through opening at one side in the counter-sink, a pin in said socket, a disc carried by the

pin and seated in the counter-sink and having its marginal edge projecting into the inner end of said guide slot and having spaced grooves in said marginal edge adapted to register one at a time with the slot by adjustment of the disc in the counter-sink, a key on the head projecting into the counter-sink and engaging a second groove in the disc to hold the latter when adjusted, said disc also having an opening therethrough for each groove adapted to register with the opening through the head when the respective groove is in register with the guide slot, the disc further having a depression about the pin leading into said openings of the disc, and a gravity disc rotatably mounted on the pin above the first disc 10 to bear against a thread passing between the discs. 15

2. In a thread tension device, a head having a guide slot therein to receive a thread for passage over the head, a shiftable member carried by the head and having thread bearing notches therein adapted to be brought into register one at a time with the guide slot by the adjustment of said member, a pin rising from the member for receiving the thread thereacross, and a tension element 20 mounted on the pin for engaging the thread, said member having a depression adjacent the pin and the member and the head having a discharge opening leading from the depression, whereby accumulations released from the thread by the tension element may be deposited in the depression and discharged through 25 said opening.

3. In a thread tension device, a head having a 30 guide slot to loosely receive a thread, and a pair of members, one of which is movable, carried by the head and disposed in face abutting relation and adapted to receive the thread therebetween, one of said members having a discharge opening 35 therethrough over which the thread is adapted to pass whereby to release accumulations from the thread, said one member also having a marginal slot to receive the thread.

4. In a thread tension device, a supporting 40 means, a round plate carried by said supporting means and capable of rotation with respect to said supporting means, means for normally holding said plate against rotation, said plate having circumferentially spaced peripheral notches, and a plurality of spaced openings inwardly of the 45 peripheral edge thereof, and a friction member supported for movement relative to said plate, a selected notch in said plate receiving the thread 50 therein and said openings being so arranged that an opening will underlie the thread when the plate is turned to receive the thread in a particular notch thereof, the opening underlying the 55 thread constituting a discharge opening to discharge the accumulations from the thread.

5. In a thread tension device, a head having 60 a guide slot therein to receive a thread for passage over the head, a shiftable member carried by the head and having thread bearing notches therein adapted to be brought into register one at a time with the guide slot by the 65 adjustment of said member, said member and the head having a discharge opening whereby accumulations released from the thread may be deposited and discharged through said opening, and a tension element supported for movement relative to the member. 70
